UNITED STATES PATENT OFFICE.

FREDERICK OTTO MUELLER, OF ST. LOUIS, MISSOURI, ASSIGNOR, BY MESNE ASSIGNMENTS, TO BURROUGHS ADDING MACHINE COMPANY, A CORPORATION OF MICHIGAN.

CALCULATING MACHINE.

Application filed April 11, 1921. Serial No. 460,254.

To all whom it may concern:

Be it known that I, FREDERICK OTTO MUELLER, a citizen of the United States, residing at St. Louis, Missouri, have invented 5 a certain new and useful Improvement in Calculating Machines, of which the following is a full, clear, and exact description, such as will enable others skilled in the art to which it appertains to make and use the same, reference being had to the accompanying drawings, forming part of this application.

This invention relates to new and useful improvements in calculating machines, the 15 object being to provide means for compelling the completion of the multiplying operations and for locking the step-back and release mechanisms so that the rear totalizer wheels can not be shifted laterally 20 during the calculating operations of the machine, and is designed particularly as an improvement on calculating machines of the type disclosed in United States Letters Patent No. 1,317,604, dated September 30, 1919, 25 and United States Letters Patent No. 1,336,904, dated April 13, 1920.

In multiplying operations of the calculating machines of the type disclosed in the above patents, the machine is given two complete operations, the tens multiplying plates being actuated during the first operation to introduce into the rear totalizers the tens partial product and the units multiplying plates being actuated during the second operation to register the units partial products.

The machine is operated by a motor which is adapted to be thrown into and out of engagement with the actuating mechanism of 40 said machine by a vertically movable clutch operating bar having a laterally projecting pin in its upper end. The ends of this pin occupy notches formed in the upper edges of longitudinally movable bars horizontally 45 disposed on each side of the upper end of said vertical bar, one of said bars being adapted to be operated by the depression of the multiplier keys, and the other being adapted to be actuated by the depression of 50 the motor key.

When either the "1" or the "zero" multiplier key is struck, the corresponding longitudinal bar is moved forwardly causing the pin in the upper end of the vertical clutch

operating bar to ride upon the rearwardly inclined portion of the notch, thereby raising said clutch bar and throwing the motor into engagement with the actuating mechanism of the machine. The forward movement of the longitudinal bar will bring the straight upper edge thereof under the pin and hold the clutch bar against downward movement until the longitudinal bar is released and restored to its normal position just before the operating shaft completes a single stroke. When the "2" or any multiplier key of higher digital order is depressed, the motor will through suitable mechanism cause the operating shaft of the machine to be given two complete operations with the exception of the "1" key and the zero key, these causing the motor to drive the operating shaft only one complete revolution. In the actual use of the machine, the multiplier keys are sometimes "whipped" or struck quickly so that the longitudinal bar is not moved forwardly a sufficient distance to position the pin on the straight edge thereof, in which case the pin carried by the clutch operating bar returns immediately to its position in the notch, so that the motor, while effecting a single stroke of the operating shaft, is disengaged before the actuating mechanism of the machine is given its possibly intended two complete operations.

In order to compel the longitudinal bar to move forwardly the full distance and retain the pin of the clutch operating bar in its operative position for the second multiplying operation of the machine, when necessary, the present invention contemplates a mechanism operable by the operation of the tens plate, which mechanism is set in position so as to prevent return movement of the longitudinal bar until the machine has been insured of the completion of its multiplying operations.

Another object of the invention is to provide means for locking the release key and the step-back key during the multiplying operations of the machine. The release key and the step-back key are decimating keys which are used after the multiplication of numbers containing decimals to eliminate the unnecessary decimals thereof. The release key when operated causes the escape-mechanism which controls the escape-

ment of the totalizer shaft to be released so as to allow the rear totalizer wheels to be shifted laterally to their normal or home position at the right side of the machine.

5 When the step-back key is operated, the rear totalizer wheels are caused to return one step at each operation thereof toward the normal position at the right. In order to lock said keys, the locking means cooperate 10 with the step-back and release mechanisms and hold them inoperative during the multiplying operations. This locking mechanism is operatively connected with the longitudinal bar so that the depression of any multiplier key will cause said locking means to disable the step-back and release mechanisms.

Figure 1 is a skeletonized view of the machine showing in full lines the longitudinal 20 bar operated by the multiplier keys and the locking mechanism for the release and step-back keys.

Figure 2 is a top plan view of the front and rear totalizers and their carrying frames.

25 Figure 3 is a detail perspective view of one of the multiplying keys and its connections.

Figure 4 is a detail view of the step-back and release keys.

Figure 5 is a detail view of the rear portion of the machine showing the location 30 of the multiplying section.

Figure 6 is a vertical cross-section through the multiplying section showing one of the tens multiplying plates in raised position.

35 Figure 7 is a horizontal cross section on line 7-7 of Figure 6.

Figure 8 is a side elevation of the locking mechanism for the step-back and release keys and showing the parts thereof ready for the 40 first operation and after a multiplier key has been depressed.

Figure 9 shows the position assumed by the parts shown in Figure 8 during the first half of the second operation.

45 Figure 10 is a plan view of parts shown in Figure 5 in normal position.

Figure 11 is a plan view of parts shown in Figure 8.

Figure 12 is a plan view of parts shown 50 in Figure 9.

Referring by numerals to the accompanying drawings, 1 indicates the frame of the machine, the keyboard of which is equipped with the usual adding keys 2 and multiplier 55 keys 4. The latter when depressed operate bell-cranks 5 which are connected by rods 6 to horizontally disposed bars 7 which extend rearwardly under the vertically disposed units multiplying plates 8 and tens multiplying plates 9. The rear ends of bar 7 which pass beyond plates 8 and 9 are provided with upwardly presented extensions 10 having vertically disposed notches 10^a. Occupying each notch 10^a is a pin 11 projecting laterally from the lower end of the

pawl 12 which is mounted for rocking movement on the horizontally disposed rod 13, the latter being carried by side walls 14 of the multiplying section. Normally, the upper end of each pawl 12 is held under the rearwardly extending arm of the bell-crank 15 and prevents the downward movement thereof. One of these bell-cranks is pivotally supported on each tens multiplying plate 9 and is pressed downwardly by the free end 75 of a spring 14^a carried by each plate. Each pawl 12 has a rearward extension to which is connected spring 16 which tends to hold said pawl in engagement with the corresponding bell-crank 15 whereby said bell-crank is held in inoperative position.

Adjoining each pawl 12 and pivotally supported on rod 13 is a pawl 17 having a shoulder 18 which is normally held by a spring 19, connected to each pawl, under the horizontal arm of a bell-crank 20, the latter being pivotally supported on a unit multiplying plate 8. The upper ends of the pawls 17 extend upwardly a predetermined distance above the bell-cranks 20 and are provided 85 with projections or pins 21. A pawl 17 having a pin 21 is provided for each unit multiplying plate, except the zero and "1" plates which are operated by the depression of the zero and "1" multiplying keys. Each pin 95 21 lies in the path of upward movement of a heel portion 9^a extending rearwardly from a corresponding tens multiplying plate. A spring 22 is connected with each pawl 17 and tends to hold shoulder 18 in engagement 100 with the corresponding bell-crank 20. A horizontal bar 24 is arranged for vertical movement in the side walls 14 of the multiplying section and normally rests below the lower ends of crank arms 15 and 20. One 105 end of said bar 24 extends through the side wall 14 and is connected by a link 25 to an arm 26 which is fixed to shaft 27, the latter being suitably journaled on the base of the machine. A pinion 28 is fixedly mounted 110 on shaft 27 and meshes with a segment 29, arranged to receive rocking motion through suitable connections (not shown) which connections operatively connect the segment with the motor.

Each bar 7 is provided with an upward projection 7^a the forward edge of which bears against one end of a toggle joint consisting of a rearwardly extending plate 31, the forward end of which is pivotally 120 mounted in bearings formed on the base, while the rear end is pivotally connected to the lower end of plate 32. Plate 32 is inclined rearwardly and its upper end contacts with the extensions 7^a on each bar 7. 125 A bar 34 is longitudinally disposed on the base of the machine adjacent to segment 29 and its rear end 35 extends upwardly and is provided with a notch 35^a in which is positioned a pin 36, the latter projecting from 130

one side of plate 32. Bar 34 is slideable in its bearings and its upper edge is provided with a notch 34^a having an upwardly inclined face. Occupying this notch is a transverse pin 37 fixed in the upper end of a motor clutch operating bar 38.

Pivotedly mounted on the side walls 14 above pawls 12 and 17 is a horizontally disposed member 39 having an inwardly projecting portion 39^a which lies in the path of upward movement of heel portions 9^a on plates 9. Rocking member 39 is connected by a link 40 to a bell-crank 41 pivotally mounted in the lower portion of one of the side walls 14. A forwardly extending bar 42 is pivotally connected at its rear end to bell-crank 41 and is provided at its forward end with a horizontally disposed pin 44 which is designed to bear against the rear edge of projection 35.

In the multiplying operation of the machine, the depression of any one of the multiplier keys will move its corresponding bar 7 forwardly rocking pawl 12, thereby releasing its corresponding bell-crank 15 so that its lower end will be moved outwardly and forwardly by spring 14^a into a position where it can be engaged by the upwardly operating bar 24, so that the tens multiplying plate on which said bell crank is mounted will be raised into operative position. Simultaneously upward projection 7^a on the actuating bar 7 strikes the upper end of plate 32, moving it and pin 36 carried thereon and occupying notch 35^a in the rear end of bar 34 forwardly. The forward movement of bar 34 causes pin 37 in the upper end of bar 38 to ride upon the inclined portion of notch 34^a and rest on the straight upper edge of bar 34. The upward movement of bar 38 connects the motor to the actuating mechanism of the machine so that segment 29 is rocked on shaft 30 thereby imparting rotary motion to shaft 27. Arm 26 carried by said shaft causes bar 24 to which it is operatively connected by arm 25 to move upwardly. In its upward movement bar 24 will engage the lower end of the released bell-crank lever 15 and carry it and its corresponding tens multiplying plate upwardly.

The zero and "1" tens multiplying plates, each requiring only one operation of the machine, are not provided with heel portions 9^a, so that rocking member 39 is not affected by their operation, and, consequently, pin 44 is not moved forward. The remaining tens multiplying plates being provided with heel portions 9^a, their upward movement will bring their corresponding heel portions against the inwardly projecting portion 39^a and cause member 39 to rock on its pivots. This rocking motion will be imparted to bell-crank 41 through link 40 causing it to move bar 42 forwardly. Pin

44 carried by the forward end of link 42 is moved forward a predetermined distance and being positioned immediately behind the rear end of bar 34 will compel said bar to travel its full distance forward so that pin 37 is properly positioned on the straight upper end of bar 34 and is caused to remain in this position until bar 34 is released by suitable mechanism, not shown, thereby insuring the second operation of the machine, which is necessary in completing the multiplying operations. When bar 34 is released and restored to its normal position, it will through its engagement with pin 44 restore bell-crank 41 and member 39 to their normal positions.

The release and step-back keys 45 and 46 control the lateral movement of the rear totalizer shaft 47 toward its right or normal position. The release key 45 is pivotally mounted in the frame of the machine and when depressed operates bell-crank 48 which is connected by rod 49 to arm 50 loosely mounted on shaft 51. Step-back key 46 is pivotally mounted in the frame of the machine and adjacent to release key 45 and operates bell-crank 52 which is connected by rod 54 to arm 55, the latter being fixed to shaft 51. A vertically movable rocking bar 56 is connected at its lower end to arm 57 which is fixed to shaft 51 and the upper end of said bar is adapted to operate pawls 58, said pawls being adapted to cooperate with escapement teeth on shaft 47. When the step-back key is depressed bar 56 operates pawls 58 so as to permit shaft 47 and the totalizer wheels carried thereby to step back one space towards the right or normal position.

Arm 59 is conjoined to arm 50 and is connected to lever 60 by rod 61. When the release key is operated, lever 60 is actuated by said key to rock arm 56 and cause it to operate pawls 58 to release shaft 47 and permit it to return to its home position. In Figure 4 the step-back key is shown depressed, and in Figure 5 arms 55 and 57 are shown in moved position being operated by the depression of the step-back key, and bar 56 is raised so that escapement pawls 58 are thrown out of engagement with shaft 47, thereby releasing same for movement one step back or towards its normal position.

Pivotedly supported on the frame of the machine and rearwardly of arms 55 and 56 is a plate 62 the forward end of which is bifurcated to form extensions 62^a and 62^b. Extension 62^a is located adjacent to the downwardly depending arm 55, and its forward end is bent downwardly and normally is positioned above lateral projection 55^a on arm 55. This projection can be formed by having the end of the screw which forms pivotal connection between rod 54 and arm 55 project outwardly a slight distance from

- arm 55. Similarly, the forward end of extension 62^b is bent downwardly and is normally positioned above the lateral projection or screw 50^a projecting from arm 50.
- 5 On the underside of plate 62 is pivoted the rear end of pawl 64, the forward end of which is adapted to normally rest on the upper portion of segment 29. A spring 65 connected to pawl 64 tends to hold said 10 pawl in a downward position. A horizontal lever 66 is transversely mounted on base 3 by pivotal connection 67. The rear or inner end of this lever rests against the rear end of bar 34 and is yieldingly connected thereto by spring 68, one end of said 15 spring being connected to pin 69 carried by said lever and the other end of said spring being connected to pin 34^a carried by bar 34. The outer end of lever 66 20 is bent upwardly and pivotally mounted on the upper end thereof is a tappet 70 having its upper end beveled or inclined and normally bearing against lug 71, which lug is formed on the underside of plate 62. Tappet 70 is held in engagement with lug 71 25 by a spring 72 carried by the lever 66 and connected to said tappet. The forward end of pawl 64 rests on pin 74 projecting laterally from tappet 70. Pawl 64 is held downwardly by spring 65 and is provided with 30 a shoulder 75 which is designed to engage pin 74 and hold tappet 70 in disabled position when lever 66 is actuated.
- In Figure 5, arm 55 is shown moved forwardly and bar 56 is raised to operate escapement pawls 58. When in normal position, arm 55 will be in alinement with arm 50 so that pin 55^a carried by arm 55 and pin 50^a carried by arm 50 are located 35 rearwardly of the downwardly extending portions of extensions 62^a and 62^b. When plate 62 is released, these forward extensions move downwardly and their downwardly extending portions will be positioned 40 in front of the pins 55^a and 50^a, so that the forward or operating movement of arms 50 and 55 is blocked, thereby locking the step-back and release mechanisms against 45 operation. Normally, plate 62 and lever 66 50 and parts associated therewith occupy positions as shown in Figures 5 and 10.
- When a multiplier key is operated, the bar 34 is shifted forwardly, the inner end of lever 66 being connected to the rear end of 55 said bar by spring 68, said lever will be operated to move its upwardly extending end rearwardly. This will cause the tappet 70 pivotally mounted thereon to move rearwardly and disengage its upper end from 60 lug 71 so that pin 74 occupies a position immediately in the rear of shoulder 75 of pawl 64, as shown in Figures 8 and 11. Plate 62 being no longer held in raised position by tappet 70, is pulled downwardly by 65 spring 65 so that the projections 62^a and 62^b will engage pins 55^a and 50^a carried by arms 55 and 50, respectively.
- As before stated, in multiplying operations involving multiplier keys of higher denomination than zero and "1," the machine 70 is required to perform two complete operations. In order to hold the step-back and release mechanisms locked during the second operation, bar 34 and lever 66 being restored to their normal position at the completion of 75 the first operation, pawl 64 is provided with a shoulder 75, which is adapted to engage pin 74 on tappet 70 and hold said tappet in disabled position during the second operation of the multiplying mechanism, as shown 80 in Figures 9 and 12. Segment 29 is arranged to strike the forward end of pawl 64 and maintain it in a slightly raised position when said segment is in its "home" or normal position. Consequently, when segment 85 29 is rocked downwardly during the first operation, pawl 64 moves downwardly under the influence of springs 65 and engages pin 74 so that when lever 66 is restored, said pawl will prevent the return movement of 90 the upper end of tappet 70 into engagement with the lug 71 on plate 62. Upon the completion of the multiplying operations, segment 29 is returned to its normal position and moves pawl 64 upwardly out of engagement with pin 74 so that tappet 70 is restored to its home position by spring 72. This restoration of tappet 70 brings the upper end thereof into engagement with lug 71 so that plate 62 is rocked upwardly and 100 extensions 62^a and 62^b are raised out of engagement with projections 55^a and 50^a thereby by releasing the arms 55 and 50 for operation.
- What I claim is:
1. In a calculating machine, the combination of multiplying plates, means for operating said multiplying plates, and means positively operable by one of said multiplying plates for causing the first mentioned 105 means to perform its intended operation.
2. In a calculating machine, the combination of a register, plates for obtaining tens and units partial products, and introducing them into said register, means for operating said plates, and positive means for insuring necessary consecutive operation of said plates.
3. In a calculating machine, the combination of a product register, plates for introducing partial products therewith, and means controlled by the operation of one of said plates for positively insuring the operation of the other of said plates.
4. In a calculating machine, the combination of a product register, means for stepping the same progressively to higher denominations, means for restoring said register to home position retrogressively, and a trap for controlling said means so that one 125 130

means is locked against the movement of the other.

5. In a calculating machine, the combination of a product register, means for advancing the same to higher denominations, an escapement mechanism which may be released to permit the return of said product register to its normal or home position, means whereby said product register may be returned step by step to its home position, a power shaft, and means for preventing the operation of the product register returning means during the operation of the power shaft.
- 10 6. In a calculating machine, the combination of a multiplying plate, a key for operating the plate, a motor operating bar positioned by the key, and means controlled by the plate for preventing the untimely restoration of said motor bar.
- 15 7. In a calculating machine, the combination of a multiplying plate, a key for operating said plate, a motor operating bar positioned by the key, and means operated by said plate for cooperating with said key in positioning said motor bar, to insure the necessary sequential operations of said machine.
- 20 8. In a calculating machine, the combination of a power shaft, multiplying mechanism operable thereby, said multiplying mechanism including a product register, restoring means for the product register, and means operable by the power shaft and in control of said register restoring means.
- 25 9. In a calculating machine, the combination of a key, motor driven multiplying mechanism having a product register, a bar for controlling the motor drive of said multiplying mechanism and operatively positioned by said key returning means for the product register, and means controlled by said motor bar for rendering inoperative said returning means.
- 30 10. In a calculating machine, the combination of multiplying mechanism having laterally movable totalizer wheels, escapement mechanism therefor, and means operable by said multiplying mechanism for automatically locking said escapement mechanism when said multiplying mechanism is actuated.
- 35 11. In a calculating machine, the combination of multiplier keys, totalizer wheels, an escapement mechanism therefor, a manually operable step-back key adapted to operate said escapement mechanism whereby said totalizer wheels are returned to their normal position one step at a time, a manually operable release key adapted to operate said escapement mechanism whereby said totalizer wheels are restored to their home position, and means operable by said multiplier keys for locking said step-back and said release keys against operation.
- 40 12. In a calculating machine, the combination of multiplier keys, multiplying mechanism including vertically movable plates, motor engaging and disengaging means for said multiplying mechanism, and means actuated by the vertical movement of said multiplying plates and adapted to compel said motor engaging and disengaging means to positively move into engaging position.
- 45 13. In a calculating machine, the combination of multiplier keys, multiplying mechanism including vertically movable multiplying plates, motor controlling means, a pivotally supported transverse member adapted to be actuated by said plates, and means actuated by said transverse member and adapted to positively hold said motor controlling means in operative position.
- 50 14. In a calculating machine, the combination of multiplier keys, multiplying plates movable in vertical plane and provided with rearwardly projecting portions, a longitudinally movable bar for controlling the driving connections of the machine and operable by said keys, a pivotally mounted member adapted to be actuated by said rearwardly extending portions, a longitudinally disposed link having its forward end in operative engagement with said bar, and means operable by said pivotal member and adapted to move said link forwardly.
- 55 15. In a calculating machine, the combination of multiplying plates movable in vertical plane and having rearward extensions, a rocking plate pivotally mounted above said extensions and adapted to be actuated thereby, a horizontal bar movable longitudinally to establish driving connections for said machine, and a longitudinally movable link operable by said rocking plate and adapted to positively position said horizontal bar in driving engagement.
- 60 16. In a calculating machine, the combination of multiplier keys, vertically movable plates provided with rear heel portions, a rocking plate positioned above and in the path of movement of said heel portions and arranged to be actuated thereby, a movable bar operable by said keys to establish driving connections for said machine, and a movable member operable by said rocking plate for retaining said bar in operative position whereby the completion of multiplying operations is insured.
- 65 17. In a multiplying mechanism for calculating machines, the combination of keys, multiplying plates movable in vertical plane, rearwardly projecting extensions on said plates, means operable by said keys for controlling the driving connections of said multiplying mechanism, and means operable by said extensions for preventing the return movement of said drive controlling means before the completion of the multiplying operations.

18. In a multiplying mechanism for calculating machines, the combination of vertically movable multiplying plates, actuating mechanism therefor, means for controlling the driving connections of said actuating mechanism, a longitudinal bar movable in a horizontal plane and adapted to position said drive controlling means in operative position, a rocking member positioned in the path of movement of said multiplying plates whereby said rocking member is actuated, and means operable by said rocking member for positively blocking the return movement of said longitudinal bar.
19. In a calculating machine, the combination of multiplier keys, a motor bar operable by said keys, multiplying mechanism provided with laterally movable totalizer wheels, an escapement mechanism for permitting lateral movement of said totalizer wheels toward their normal position, and means for locking said escapement mechanism when the multiplying mechanism is actuated, said locking means being operable by the actuation of said motor bar.
20. In a calculating machine, the combination of multiplier keys, a longitudinally movable motor bar operable by said keys, multiplying mechanism having laterally movable totalizer wheels, escapement mechanism for permitting the lateral movement of said totalizer wheels towards their normal position, means for locking said escapement mechanism, a lever having cooperative connection with said motor bar and displaceable means associated with said lever and adapted to normally hold said locking member inoperative, said displaceable means being arranged to be displaced when said lever is actuated whereby said locking member is rendered operative.
21. In a calculating machine, the combination of multiplier keys, multiplying mechanism having laterally movable totalizer wheels, a motor bar operable by said keys, escapement mechanism for said totalizer wheels, step-back mechanism for actuating said escapement mechanism whereby said totalizer wheels are shifted laterally one step towards their normal position, and locking means associated with said motor bar and adapted to lock said step-back mechanism when a multiplier key is operated.
22. In a calculating machine, the combination of multiplier keys, a motor bar operable by said keys, multiplying mechanism including laterally movable totalizer wheels, step-back mechanism adapted to move said totalizer wheels one step towards their normal position, a rocking member for locking said step-back mechanism, a lever cooperating with said motor bar, and means adapted to move said locking member into operative or inoperative position.
23. In a calculating machine, the combination of multiplier keys, a motor bar operable by said keys, multiplying mechanism including laterally movable totalizer wheels, step-back mechanism adapted to move said totalizer wheels one step towards their normal position, a rocking member for locking said step-back mechanism, a lever cooperating with said motor bar, means pivotally mounted on said lever and adapted to move said locking member into operative or inoperative position, and a member adapted to engage said means and hold it in disabled position.
24. In a calculating machine, the combination of multiplier keys, a motor bar operable by said keys, laterally movable totalizer wheels, escapement mechanism for said totalizer wheels, a release key for actuating said escapement mechanism whereby the totalizer wheels are restored to their normal position, a pivotally mounted plate adapted to be moved into operative position and lock said release key, a lever having yielding operative connection with said motor bar, and a displaceable member carried by said lever and normally in engagement with said plate, whereby said plate is rendered inoperative, said displaceable member being adapted to be moved by said lever out of engagement with said plate, whereby said plate is rendered operative to lock said release key.
25. In a calculating machine, the combination of multiplier keys, a motor bar operable by said keys, laterally movable totalizer wheels, escapement mechanism for said totalizer wheels, a release key for actuating said escapement mechanism, whereby the totalizer wheels are restored to their normal position, a pivotally mounted plate adapted to be moved into an operative position and lock said release key, a lever having yielding operative connection with said motor bar, a displaceable member carried by said lever and normally in engagement with said plate, whereby said plate is rendered inoperative, said displaceable member being adapted to be moved by said lever out of engagement with said plate, whereby said plate is rendered operative, and means for retaining said displaceable member in disengaging position.

In testimony whereof I hereunto affix my signature this 7th day of April, 1921.

FREDERICK OTTO MUELLER.
